UNITED STATES PATENT OFFICE.

NATHAN BARNEY, OF BERGEN POINT, NEW JERSEY, ASSIGNOR TO THE BARNEY DUMPING BOAT COMPANY, OF SAME PLACE.

DUMPING-SCOW.

SPECIFICATION forming part of Letters Patent No. 271,298, dated January 30, 1883.

Application filed May 26, 1882. (No model.)

To all whom it may concern:

Be it known that I, NATHAN BARNEY, of Bergen Point, in the county of Hudson and State of New Jersey, have invented certain 5 new and useful Improvements in Dumping-Boats, of which the following is a specification.

My invention relates to dumping boats or scows which are severally composed of two 10 floats or pontons, which are hinged at their upper and outer longitudinal edges, so that they may be brought together to receive the load, and when released will swing downward, and outward, so as to dump the load between 15 them and afford a clear opening from end to end of the boat or scow. In such boats or scows the two floats or pontons have been connected at opposite ends of the boat or scow by sectors geared together, or connected by 20 other means, so as to cause the floats or pontons to move together in opening and closing; and the principal object of my invention is to provide an effective and simple means for holding the floats or pontons together to receive and carry the load, for controlling or retarding their opening movement, which is apt 25 to be too rapid, because of the great weight of the load and the momentum acquired in opening, and for holding them in their outermost 30 position after the load is dumped and while the boat or scow is being towed ahead, so that the water can have a clear passage between the floats or pontons, and thus wash out all 35 matters which otherwise might adhere to the float or pontons.

To this end my invention consists in the combination, with two floats or pontons, of a 40 slideway extending transversely to the same, sliding bars connected one with each float or ponton, arranged in an approximately horizontal position and adapted to move in said slideway, and means for clamping said bars together or against a suitable guide or stationary beam or resistance-piece, so that they can 45 not move one upon another or in opposite directions, as they must do to allow the floats or pontons to swing or move toward or from each other. In order to render them more effective, the sliding bars may be provided with 50 shoulders, which are made to engage with each

other by the clamping of said bars; and the means for clamping of the bars may consist of a cam on a vertical shaft acting upon a yoke which is pressed against one of said bars.

The invention also consists in the combination, with the two hinged floats or pontons, pairs of sliding bars arranged parallel with each other transversely above the floats or pontons, and connected therewith, and a cam and cam-shaft for clamping the bars of each 60 pair, of a shaft extending longitudinally of the floats or pontons, and gearing connecting said longitudinal shaft with said cam-shafts for turning them in unison.

The invention also consists in the combination, with two floats or pontons hinged as above described, and geared sectors connecting them, of projections on the sides of the sectors and spring or elastic cushions, upon which the said projections strike as the floats 70 or pontons approach the end of their outward movement away from each other, as hereinafter fully described.

In the accompanying drawings, Figure 1 represents a plan of a boat or scow embodying my 75 invention. Fig. 2 represents a transverse section of the boat or scow upon the dotted line $x\ x$, Fig. 1. Fig. 3 represents a similar section upon the dotted line $y\ y$, Fig. 1. Fig. 4 represents a transverse section of a pair of sliding 80 bars, which are connected with the floats or pontons, and the mechanism for clamping them, upon a larger scale. Fig. 5 represents a horizontal section of the parts shown in Fig. 4, 85 upon the same scale.

Similar letters of reference designate corresponding parts in all the figures.

A A' designate the two floats or pontons, which together form the scow or boat, and which may be constructed in any suitable manner to secure the desired strength and buoyancy.

At or near each end of the boat or scow is a platform or deck portion, B, and intermediately between the ends is a third platform or deck 95 portion, B'.

The floats or pontons are secured or hinged to the platforms or deck portions B B' by hinges or pivots α along their upper and outer longitudinal edges, so that they may swing 100

freely downward and outward when released, and the upper or load-supporting surfaces of the floats or pontons are inclined downward and inward toward each other at an angle of 5 about forty-five degrees, (45°,) as clearly shown in Figs. 2 and 3.

Near each end of the two floats or scows A A' they are provided with sectors C, which are geared together and cause the floats or 10 pontons to move in unison toward and from each other.

The sectors are provided on their sides with studs or projections b, and as the floats or pontons reach the end of their outward movement 15 the projections strike upon stops c, made of india-rubber springs or other elastic or spring material, and which form cushions for checking the movement of the floats or pontons.

In each platform or deck portion B B' is a 20 slideway, B², extending transversely to the boat or scow, and in such slideway is arranged a pair of sliding bars, D D', which are parallel with each other. The bars D D' are connected with the two floats or pontons by rods, 25 as best shown in Fig. 2, the bar D being connected by a rod, E, with the float or ponton A, and the bar D' being connected by a similar rod, E', with the float or ponton A'. It will therefore be seen that when the floats or 30 pontons swing outward the bars D D' will be moved or slid through the rods E E' in opposite directions, and if said bars are locked or held against movement the floats or pontons cannot swing on their hinges either toward or 35 from each other.

Adjacent to each pair of bars D D' is a vertical shaft, F, carrying at its lower end a cam, d, and said cam is arranged in an open yoke or shoe, e, which it presses against one of said 40 bars when the shaft is rotated. On the opposite side of the bars D D' from the shaft F is a beam or wall, f, against which one of said bars is pressed, and by the joint action of the cam d and the beam or resistance-piece 45 f the bars are clamped securely together and are held against movement one upon the other.

Upon their adjacent faces the bars D D' may have shoulders, g, which engage with each other, as shown best in Fig. 5, when the 50 floats or pontons are closed or brought together, and the bars are pressed together or clamped, and by this means the floats or pontons are held against swinging outward in a very secure manner.

In order to enable all the vertical cam-shafts to be turned together, I provide a shaft, G, extending longitudinally of the boat or scow, and provided with a hand-wheel, G', whereby it may be turned.

Upon the shaft G are bevel pinions or wheels, h, which engage with similar pinions, i, on the cam-shafts F, and effect the turning of the latter, and by this means all the pairs of bars D D' may be clamped together simultaneously 65 and simultaneously released.

When the boat is to receive its load the sev-

eral pairs of bars D D' are clamped together, and the floats or pontons are held together by them until it is desired to dump the load. The shafts F are then turned to release the bars, 70 and the weight of the load will cause the floats or pontons to swing outward or apart, and the bars of each pair will move or slide one upon another. It is desirable that the floats or pontons should be prevented from 75 swinging outward too rapidly, and this effect by not entirely releasing the sliding bars, but by pressing them together with such force as to create considerable friction by their movement, which will of course retard or regulate the swinging movement of the floats or 80 pontons.

When the floats or pontons reach the end of their outward movement the shaft G is turned so as to clamp all the pairs of bars D D', and 85 the floats or pontons are thus held apart, while the boat or scow is towed slightly ahead. The water now has a clear passage between the floats or pontons, and the towing ahead of the boat or scow leaves all the light floating 90 garbage behind, and washes off the floats or pontons any material which would otherwise stay upon them. The sliding bars D D' are then released, and the floats or pontons are free to swing inward by their buoyancy and 95 will swing inward close together.

It will be seen that the pairs of sliding bars form a very simple and effective means for holding or locking the floats or pontons together or apart, and for regulating or controlling the swinging movement of the floats or 100 pontons.

In order to prevent the longitudinal movement of either float or ponton independently of the other in case of collision or striking a 105 dock or other obstacle, I provide one float with a lug, j, which fits between lugs j' on the other float, as clearly shown in Fig. 1.

What I claim as my invention, and desire to 110 secure by Letters Patent, is—

1. The combination, with the two hinged floats or pontons of a dumping boat or scow, of a slideway extending transversely to the same, sliding bars arranged in approximately horizontal positions, connected one with each 115 float or ponton, and adapted to move in said slideway, and means for clamping said bars to hold them against movement, substantially as and for the purpose described.

2. The combination, with the two hinged floats or pontons of a dumping boat or scow, of sliding bars connected one with each float or ponton, and provided with shoulders on their adjacent faces, and means for clamping said bars together, substantially as and for the purpose herein described.

3. The combination, with the two hinged floats or pontons of a dumping boat or scow, of a slideway extending transversely to the same, sliding bars connected one with each float 125 or ponton, and adapted to move in said slideway, and a cam and cam-shaft for clamping

- said bars, substantially as and for the purpose herein described.
4. The combination of the hinged floats or pontons A A', the sliding bars D D', arranged parallel with each other and transversely above the floats or pontons, the rods E E', connecting the floats or pontons with said bars, and means for clamping said bars, substantially as herein described.
5. The combination of the floats or pontons A A', the pairs of sliding bars D D', arranged parallel with each other and transversely across above the floats or pontons, the rods E E', connecting said floats or pontons with said bars, the cams d, the upright cam-shaft, F, the shaft G, extending longitudinally of the boat, and gearing connecting the cam-shafts with said shaft G, substantially as herein described.
6. The combination of the floats or pontons A A', the geared sectors C, provided with projections b on the side, and the elastic or spring cushions c, substantially as herein described.

N. BARNEY.
